UNITED STATES PATENT OFFICE.

WILLIAM H. DE BUSK, OF CHICAGO, ILLINOIS, ASSIGNOR TO THE P. & M. COMPANY, OF CHICAGO, ILLINOIS, A CORPORATION OF ILLINOIS.

RAIL ANCHOR.

Application filed November 18, 1924. Serial No. 749,656.

To all whom it may concern:

Be it known that I, WILLIAM H. DE BUSK, a citizen of the United States, and a resident of Chicago, in the county of Cook and State 5 of Illinois, have invented certain new and useful Improvements in Rail Anchors, of which the following is a specification, reference being had to the accompanying drawings.

10 My invention relates to rail anchors of the type adapted when applied to a rail in contact with a crosstie or other fixed part of a roadbed to hold the rail from movement longitudinally. It is the principal 15 object of my invention to provide a construction of this type in which a jaw member is held in gripping position by means of a clip adapted to be swung from a position at one side of the rail into engagement with 20 the upper face of the flange of the rail, the arrangement being such that in the swinging movement of the clip into operative position the clip passes an intermediate critical point beyond which the clip is permitted to 25 loosen very slightly whereby the pressure of the jaw member upon the clip tends to hold the clip in operative position.

It is another object of my invention to improve devices of this type in sundry details hereinafter pointed out. The preferred 30 means by which I have accomplished my several objects are illustrated in the drawing and are hereinafter specifically described. That which I believe to be new and 35 desire to cover by this application is set forth in the claims.

In the drawing,—

Fig. 1 is a face view of my improved construction in position upon a rail which is 40 shown in vertical cross-section;

Fig. 2 is a top plan view of the parts shown in Fig. 1;

Fig. 3 is a view similar to Fig. 1, but showing a slightly modified form of construction; and

Fig. 4 is a top plan view of the device shown in Fig. 3.

Referring to Figs. 1 and 2 of the drawing, 5 indicates a rail of any approved type supported in position upon a crosstie 6. A jaw member comprising a body 7 is mounted upon the flange of the rail at one side thereof, said jaw member being provided with an arm 8 extending across beneath the rail 55 from one edge of the body, said arm 8 being

held tensioned and distorted slightly, as indicated by dotted lines in Fig. 1, by means of a U-clip 9 the legs of which are provided with turned end portions 10 which are adapted to engage the upper face of the 60 flange of the rail at the side thereof opposite from that at which the body 7 engages.

In the application of the device to a rail, the member 7 is first slipped into position 65 from the side of the rail; the clip 9 is then placed in position in engagement with a diagonally-disposed portion 11 of the arm 8, with the clip turned in clock-wise direction from the position shown in Fig. 1 at 70 one side of the rail, being held from withdrawal from the arm by means of a downwardly-extending end portion 12. Upward pressure is then applied upon the arm 8, until the turned portions 10 of the legs of 75 the clip are caught over the edge of the flange, whereupon the clip is driven or otherwise forced to turn in counterclock-wise direction in Fig. 1 about the point 9^a 80 into operative engagement with the flange as shown in said figure. In this turning movement of the clip, the arm 8 is first moved upwardly until the point 9^b of the clip passes the corner of the flange, and then during the latter portion of the movement 85 of the clip the arm 8 is permitted to move downwardly very slightly in the direction away from the rail, the point 9^b of the clip being determined by a perpendicular from the point 9^a to the leg 10. This downward 90 movement of the arm permitted by the clip serves to decrease very slightly the tension of the arm, but it results in a virtual locking of the clip in operative position, in that in the final applied position of the clip the 95 downward pressure upon the clip tends to move the clip toward the rail rather than away from the rail.

In Figs. 3 and 4, the jaw member is in the form of a casting rather than in the form 100 of a stamping from a plate of sheet metal, the arm 13 of this form of device being heavy enough as to resist bending to any appreciable extent. In this form the body 14 is provided with an abutment plate 15 105 formed integrally therewith, and an upwardly extending lug 16 is provided for engagement with the edge of the flange. An intermediate position of the clip 9 is indicated by dotted lines, showing the arm 13 110

necessarily elevated slightly with respect to the final operative position in order to permit the movement of the clip into its operative position.

5 By my invention, I have provided a construction having clearance between the cross arm and the bottom face of the rail in the final applied position of the device, the retaining clip being so disposed and arranged 10 that the tension upon the arm is decreased rather than increased during the final portion of the swinging movement of the clip into operative holding position.

15 While I prefer to employ the constructions illustrated in my drawing, it will be understood that I do not desire to limit myself to the precise details as shown except so far as the same are hereinafter specifically claimed, inasmuch as it is evident that 20 changes may well be made in the detailed form without departing from the spirit of the invention.

I claim:

1. In a rail anchor, the combination with 25 a member comprising jaws adapted to engage the flange of a rail at one side thereof, and an arm extending across beneath the rail in spaced relation thereto, of a clip engaging the arm and adapted to swing from a position 30 at one side of the rail into engagement with the upper face of the flange, the arrangement being such that as the clip approaches its operative position the downward pressure of the arm on the clip tends 35 to swing the clip into such operative holding position.

2. In a rail anchor, the combination with 40 a member comprising jaws adapted to engage the flange of a rail at one side thereof, and an arm extending across beneath the rail in spaced relation thereto, of a clip engaging 45 the arm and adapted to swing about an axis extending longitudinally of the rail and adapted in diagonal position to engage the upper face of the flange, the arrangement of 50 the clip being such with respect to the slope of the upper face of the flange that when the clip is in operative position the downward pressure of the arm on the clip tends to retain the clip in operative holding position.

3. In a rail anchor, the combination with 55 a member comprising jaws adapted to engage the flange of a rail at one side thereof, an arm extending across beneath the rail in spaced relation thereto, and a hook on said arm, of a clip engaging said hook and adapted to swing thereabout from a position 60 at one side of the rail into engagement with the upper face of the flange, the arrangement being such that as the clip approaches its operative holding position the downward pressure of the arm on the clip tends to swing the clip into such operative holding position.

65 4. In a rail anchor, the combination with

a member comprising jaws adapted to engage the flange of a rail at one side thereof, and an arm extending across beneath the rail in spaced relation thereto, said arm having a downwardly directed portion substantially beneath the edge of the flange, of a clip engaging the arm and held in such engagement by the downwardly directed portion, and adapted to swing from a position at one side of the rail into engagement with the upper face of the flange, the arrangement being such that when the parts are in operative gripping position the arm must be lifted slightly with respect to the flange for disengagement of the clip from the flange whereby the pressure of the arm on the clip serves to hold the clip in operative position.

5. In a rail anchor, the combination with a member comprising jaws adapted to engage the flange of a rail at one side thereof, and an arm extending across beneath the rail in spaced relation thereto and slightly offset at its end portion in the direction away from the crosstie, of a clip engaging the arm and having a portion extending along the face of the arm between the arm and the crosstie, said clip being adapted to swing from a position at one side of the rail into engagement with the upper face of the flange, the arrangement being such that as the clip approaches its operative holding position the downward pressure of the arm on the clip tends to swing the clip into such operative holding position.

6. In a rail anchor, the combination with 100 a member comprising jaws adapted to engage the flange of a rail at one side thereof, and an arm extending across beneath the rail in spaced relation thereto, of a U-clip embracing the arm and adapted to swing 105 from a position at a distance from the side of the rail into close proximity to the edge of the flange, the legs of said clip being arranged to engage the upper face of the flange of the rail, and the arrangement being 110 such that at the last portion of the swinging movement of the clip toward the flange the downward pressure of the arm on the clip tends to swing the clip into such operative holding position.

7. In a rail anchor, the combination with 115 a member comprising jaws adapted to engage the flange of a rail at one side thereof, and an arm extending across beneath the rail in spaced relation thereto and slightly offset at its end portion in the direction away from the crosstie, of a U-clip embracing the arm and adapted to swing from a position at a distance from the side of the rail into close proximity to the edge of the flange, the legs 120 of said clip being arranged to engage the upper face of the flange of the rail, and the arrangement being such that at the last portion of the swinging movement of the clip 125 toward the flange the arm is permitted to 130

move downwardly very slightly with respect to the flange whereby the downward pressure of the arm on the clip in its operative holding position tends to hold the clip in such operative holding position.

8. In a rail anchor, the combination with a member comprising jaws adapted to engage the flange of a rail at one side thereof, and an arm extending across beneath the rail in spaced relation thereto, of a clip engaging the arm and adapted to swing from a position at one side of the rail into engagement with the upper face of the flange, the arrangement being such that a portion of the swinging movement of the clip as it is forced toward the rail serves by a camming action to raise the arm with respect to the flange and that a subsequent portion of such swinging movement of the clip serves to permit the arm to move very slightly away from the flange.

9. In a rail anchor, the combination with a member comprising jaws adapted to engage the flange of a rail at one side thereof, and an arm extending across beneath the rail in spaced relation thereto, of a clip engaging the arm and adapted to swing from a position at one side of the rail into engagement with the upper face of the flange, said clip serving to hold the jaw member from backing laterally of the rail from the flange and to hold said member in such angular position with respect to the longitudinal axis of the rail as to have an effective operative grip thereon.

10. In a rail anchor, the combination with a member comprising jaws adapted to engage the flange of a rail at one side thereof, and an arm extending across beneath the rail in spaced relation thereto, of a clip engaging the arm and adapted to swing thereon about an axis extending longitudinally

of the rail for engaging the upper face of the flange, said axis being located underneath the rail in such position that the tension of the arm in the final operative position of the clip is less than the tension at an intermediate point in the swinging movement of the clip.

11. In a rail anchor, the combination with a member comprising jaws adapted to engage the flange of a rail at one side thereof, and an arm extending across beneath the rail in spaced relation thereto, of a clip comprising a portion having a pivoted engagement with the arm and a leg adapted to swing from a position at a distance from the edge of the flange into close proximity with the edge of the flange, said leg being provided with an end portion extending transversely of the rail at an acute angle with respect to the main portion of the leg for engagement with the upper face of the flange of the rail, the arrangement being such that the pressure of the arm on the clip serves normally to lock the clip in operative holding position.

12. In a rail anchor, the combination with a member comprising jaws adapted to engage the flange of a rail at one side thereof, and an arm extending across beneath the rail in spaced relation thereto, said arm being provided with means for holding the jaw member from backing transversely of the rail from the flange, of a clip engaging the arm and adapted to swing from a position at one side of the rail into engagement with the upper face of the flange, the arrangement being such that as the clip approaches its operative position the downward pressure of the arm on the clip tends to swing the clip into such operative holding position.

WILLIAM H. DE BUSK.
